(57) **CLAIM**

The ornamental design for a joiner for a modular frame system, as shown and described.

DESCRIPTION

The patent file contains at least one drawing executed in color. Copies of this patent with color drawings will be provided by the Office upon request and payment of the necessary fee.

1. Joiner for a Modular Frame System

1.1: is a perspective view of a joiner for a modular frame system according to a first embodiment of our new design;

1.2: is a plan view thereof;

1.3: is a left view thereof;

2.1: is a perspective view of a joiner for a modular frame system according to a second embodiment of our new design;

2.2: is a top view thereof; and

2.3: is a left view thereof.
